SOUND RECORDING AND REPRODUCING APPARATUS

Albert W. De Sart, Sr., Los Angeles, Calif., assignor to United Acoustigraph Corporation, Los Angeles, Calif., a corporation of Nevada

Application November 17, 1941, Serial No. 419,360

11 Claims. (Cl. 179—100.41)

This invention relates to sound recording and reproducing apparatus. More particularly it relates to stylus heads that are adapted to cooperate with a member capable of carrying a record, such as a loop, a cylinder or a disc.

Stylus heads of this general characteristic, capable of being optionally used either for recording or reproduction purposes are now well known. They usually comprise a mounting for a stylus that permits the stylus to vibrate. For recording purposes, for example, the stylus is caused to be vibrated by the aid of electrical impulses corresponding to the sounds to be recorded, there being a translator for translating the electric current impulses into a vibratory force, actuating the stylus. Such a translator may take several forms, such as an electromagnetic device or an electro-dynamic device. The movements of the stylus cause the cutting or embossing of a record groove upon a record blank.

For reproduction purposes, the grooves of the record with which the stylus is in contact impart mechanical vibration to the stylus. The mechanical vibrations are translated into electrical impulses by the translator; and these impulses (if necessary through an amplifier system) operate an air actuator, such as a telephone receiver or loud speaker; or the impulses may be used if desired for re-recording.

The groove record with which the stylus cooperates may be either of the lateral groove type or of the hill-and-dale type. In the lateral groove type, the stylus vibrates in a direction transverse to the groove, the walls of the groove carrying the undulations that represent the recorded impulses. In the hill-and-dale type, the walls of the grooves are smooth, but the bottom of the groove carries the undulations, and the stylus is in contact with these undulations.

When, for example, a stylus is cooperating with a lateral groove type of record, any temporary or permanent irregularity in the bottom of the groove is translated as an impulse. Such an irregularity may be in the form of a speck of foreign matter. The resultant operation of the apparatus is correspondingly irregular. It is one of the objects of this invention to obviate the response of the stylus to such irregularities, as by so mounting the stylus that irregular motions thereof have no effect upon the translator.

It is another object of this invention to provide a stylus head the design of which is adaptable readily to its utilization with a hill-and-dale type or with a lateral groove type record, although each specific embodiment is capable of cooperating with only one type.

It is still another object of this invention to provide an improved form of dynamic type stylus head, said dynamic type being characterized by the provision of a very light coil mounted for movement in accordance with the stylus move-

ment. By the aid of this improved form, the frequency response over the entire range of audibility is rendered more accurate.

It is still another object of this invention to provide a dynamic type of stylus head that incorporates the desired characteristics of a push-pull device, whereby greater power and a higher degree of fidelity is obtained.

This invention possesses many other advantages, and has other objects which may be made more easily apparent from a consideration of several embodiments of the invention. For this purpose there are shown a few forms in the drawings accompanying and forming part of the present specification. These forms will now be described in detail, illustrating the general principles of the invention; but it is to be understood that this detailed description is not to be taken in a limiting sense, since the scope of the invention is best defined by the appended claims.

In the drawings:

Figure 1 is a sectional view of a stylus head illustrating one form of the invention, drawn to a greatly enlarged scale, and illustrating a portion of the record blank that cooperates with the head;

Fig. 2 is a front elevation thereof, partly broken away;

Fig. 3 is a sectional view taken along plane 3—3 of Fig. 1;

Fig. 4 is a view similar to Fig. 1 illustrating the adaptation of the mechanism to a hill-and-dale type of record;

Fig. 5 is a wiring diagram illustrating the manner in which the stylus head may be connected in an appropriate circuit;

Fig. 6 is a side elevation partly in section of another form of this invention, the scale being greatly enlarged, and illustrating a portion of the record blank that cooperates with the record;

Fig. 7 is a sectional view taken along plane 1—7 of Fig. 6;

Figs. 8, 9 and 10 are detail sectional views taken respectively along correspondingly numbered planes in Fig. 6;

Fig. 11 is a sectional view taken along plane 11—11 of Fig. 6;

Fig. 12 is a pictorial view of the stylus arm illustrated in Fig. 6, and its associated elements;

Fig. 13 is a view similar to Fig. 6 of a further modified form of the invention, the figure being greatly enlarged;

Fig. 14 is a detail section taken along plane 14—14 of Fig. 13;

Fig. 15 is a view similar to Fig. 13 of a further modified form of the invention, the figure being greatly enlarged;

Fig. 16 is a pictorial view of one of the supporting elements utilized in connection with the form shown in Fig. 16;

Fig. 17 is a pictorial view illustrating the mag-

netic circuit utilized in connection with the apparatus illustrated in Figs. 6 and 7;

Fig. 18 is a view similar to Fig. 13 of a further modified form of the invention, the figure being greatly enlarged;

Fig. 19 is a sectional view taken along plane 19-19 of Fig. 18;

Fig. 20 is a wiring diagram illustrating the adaptation of the form of the invention illustrated in Figs. 18 and 19 in a complete recording and reproducing circuit; and

Fig. 21 is a fragmentary sectional view on an enlarged scale, taken on a plane 21-21 of Fig. 1.

In the form of the invention illustrated in Figs. 1, 2 and 3, a flexible member 1 capable of carrying a record is illustrated. This record carrying member may be in the form of a flexible loop or a disk or the like; it is shown in this instance as looped over a driving roller 2. The record carrying member 1 may be made from any appropriate plastic material, such as an acetate or the like.

The stylus 3 which may represent either a recording or a reproducing stylus is shown as mechanically cooperating with the record blank 1. The description of the mechanism will proceed for a recording operation, but it is to be understood that the apparatus may be used for reproduction purposes by appropriate change in connections; and if necessary by appropriate change of the character of the stylus 3.

The stylus 3 is shown as fastened in the lower end of a stylus arm 4. For this purpose the stylus arm 4 is provided with a deep aperture into which the stylus 3 is inserted. The stylus 3 is fastened in position as by the thumb screw 5.

The stylus arm 4 is arranged to vibrate about an axis provided by the aid of appropriate bearing structures. For example, the stylus arm may carry a central hub 6 (Fig. 2) provided at its opposite ends with shallow conical recesses for the reception of the cooperating conical ends of the pivot screws 7 and 8. These pivot screws are threaded within the ears 9 and 10 formed integrally with a cover member 11, which will be described in greater detail hereinafter. The screws 7 and 8 may be locked in place by appropriate lock nuts 7' and 8'.

By the aid of this pivotal mounting, vibrations of the stylus 3 are permitted about the axis of the pivot screws 7 and 8. An inspection of Fig. 1 shows that this vibration is in a direction lateral to the grooves formed on the member 1, producing a lateral groove record.

The vibrations of the stylus arm 4 are made to correspond to electrical impulses. In this way the configuration of the lateral walls of the groove are formed in accordance with these electrical impulses, such as may be produced in a circuit by a microphone or the like. The translating device whereby the electrical impulses are transformed into mechanical vibrations of the arm 4 includes in this instance an electrodynamic structure. Thus there is a magnetic frame 12 of general cylindrical configuration. This frame 12 may be appropriately supported upon a cylindrical bar 13 passing through the integrally formed ear 14. It is understood that the stylus head is caused to advance toward the right as viewed in Fig. 1 at a uniform rate in order to form the record.

The frame 12 includes an integral central core 15 which projects beyond the left hand end of the cylindrical wall 16 of the frame 12. The annular space between the core 15 and the wall

16 is used for the accommodation of a field coil 17 adapted to be supplied with direct current from any appropriate source. This coil telescopes over the central core 15.

An annular air gap 18 is formed between the extending end 18 of the core 15 and the cover member 11, which is appropriately apertured for this purpose. This cover member 11 is made from magnetic material; it is shown as supported by the annular wall 16 as by the aid of the internal threaded flange 20, cooperating with external threads on the wall. Within the narrow air gap 18 thus formed is located the axially movable dynamic coil or voice coil, comprising the axially spaced sections 21-22. When electrical impulses are fed to the coil 21-22 a dynamic force, as is well understood, is produced in an axial direction with respect to the coil.

The coil sections 21 and 22 are supported upon a very thin cylindrical support 23 having an end flange 24. These parts 23 and 24 are made from appropriate insulation or non-magnetic material. The end flange 24 is shown as mechanically connected to the upper end of the stylus arm 4. Accordingly the vibratory force created by the electrodynamic action is impressed upon the stylus arm 4 to vibrate it in accordance with the impulses imparted to the coil 21-22.

In order to provide a yielding damper against the vibration of the arm 4, use may be made of a pair of rubber-like damper members 25 disposed upon opposite sides of the arm 4. These members may be made for example of "Viscoloid." They are fastened in place at their opposite ends by the aid of the bracket members 26 shown most clearly in Fig. 2, as well as by the aid of the screws 27 which pass through the bracket members as well as through the damper members 25. These screws may be threaded into the cover 11.

In order to ensure accurate axial guiding for the movement of the voice coil 21, 22, use is made of a flexible spider structure 28 shown to best advantage in Fig. 3. The spider structure 28, which may be of paper, or of other suitable light, resilient material, is fastened adjacent its outer edge as by the aid of the screws 29 to a shoulder 30 formed around the inner edge of the cover member 11. A plurality of spring arms 31 formed integrally with the outer edge of the spider serve resiliently to support the inner hub portion 32. Into this hub portion is fastened the right hand end of the cylindrical support 23.

The coil 21-22 is shown as made in two sections, wound however in an additive sense. The annular air gap 18 is made in two parts to conform to the sections, as by the aid of the annular groove 33 formed on the cover member 11 and a corresponding annular groove 34 formed on the core extension 18. Accordingly there are formed two separated paths for the magnetism between the annular exterior surface of the extension 18 and the interior annular surface of the cover 11.

In the event that the apparatus is used for reproduction, the coil sections 21 and 22 are moved by the mechanical vibration of the stylus arm 4 produced by the record. Movement of the coil 21-22 in either direction sets up additive current impulses in the two coil sections. These current impulses may then be passed to appropriate amplifier circuits and to sound translating devices.

A push-pull amplifier circuit system is diagrammatically illustrated in Fig. 5, wherein the coil sections 21-22 correspond to the dynamic

coil. These coil sections are connected in the conventional manner to one winding 36 of a push-pull transformer 35. The other winding 37 is connected appropriately to a push-pull amplifier system 38 which may be connected to the transducer 39. If the transducer 39 is a microphone the push-pull amplifier circuits amplify the microphone currents and finally pass the amplified impulses to the coil sections 21 and 22. In the event that the system is used for reproducing purposes the transducer 39 is a telephone receiver or loud speaker or the like, fed with amplified impulses through the amplifier circuit 38, the input side of which is now connected to the transformer coil 37.

In the form illustrated in Fig. 1, the stylus 3 is adapted to form, or reproduce from, a lateral groove record. It is possible by simple arrangement of the parts to provide hill-and-dale recording or reproducing. Such a form is illustrated in Fig. 4.

The stylus arm 40 is shown in this instance as pivotally supported by the aid of the ears 41 formed on the cover member 42. The stylus arm 40 supports the stylus 43 in a direction transverse to the length of the arm 40; and the axis of the core 15 is made substantially parallel with the axis of the stylus 43. Accordingly the mechanical vibrations imposed upon the arm 40 either in recording or reproducing effects the axial position of the dynamic coils in the same manner as before; but these mechanical vibrations are produced by motion of the stylus 43 in a direction substantially along the axis of the stylus.

In the form of the invention illustrated in Figs. 6 to 12 and 17, the member 44 corresponds to the record carrying member 1 of Fig. 1. This record carrying member 44 is shown in this instance as carried over a roller 45.

Cooperating with the member 44 is a stylus arm 46. The stylus arm 46 in the present instance is intended to produce or reproduce a lateral groove record. The stylus 47 (Figs. 6, 11 and 12) is shown as appropriately fastened into an enlarged boss 48 carried at the right hand extremity of the arm 46. By the aid of a movable supporting mechanism the entire stylus head is moved toward the right as viewed in Fig. 11 over the roller 45. For this purpose there is diagrammatically indicated a movable supporting arm 49 (Figs. 6 and 7). To the right hand extremity of the arm 49 is fastened the stylus head as by the aid of a pair of screws 50. These screws engage a base member 51 forming the main support for the stylus head. A cover or casing 53 as of sheet metal may have its lower edge telescoped over the edge of the base 51 and may be fastened as by the aid of screws 52 to the base 51.

The stylus arm 46 is arranged for vibratory movement about an axis 54 (Figs. 6 and 11).

The arrangement is such that vibratory movement of the stylus arm 46 about the axis 54 forms the useful movement of the arm; and any movement about an axis transverse to the axis 54 has no effect upon the translating device that converts mechanical vibrations into electrical impulses (for reproduction) or vice versa (for recording). Any minor irregularities in the bottom of the record groove either in permanent form or as small particles of foreign matter have no effect upon the useful movement of the moving element of the translating device.

In order to ensure these results a long and accurate bearing guide is provided for the stylus

arm 46. The bearing structure incorporating this guide nevertheless is so arranged as to provide a minimum of friction, while yet ensuring complete restraint of the stylus arm vibration about the axis 54. The structure by the aid of which this is accomplished will now be described.

The stylus arm 46 for the sake of lightness and rigidity is shown as formed of a tubular element. Its left hand end as viewed in Fig. 6 and 10 as indicated in Fig. 12 is accommodated in a shallow concave saddle formed on the bottom end of a generally cylindrical member 55. This member 55 extends through an aperture 200 in base 51. Member 55 forms the moving portion of the bearing structure. The arm 46 may be appropriately attached to this element 55 as by the aid of a screw 56 (Fig. 6), which passes diametrically through the stylus arm 46.

The cylindrical member 55 forms a series of knife edges axially spaced along the axis 54, at least some of them being angularly offset from others. Thus for example, adjacent the lower part of the member 55 a cut-out portion is formed to provide the knife edge 56' (Figs. 10 and 12). Immediately above the knife edge 56 the cylindrical member 55 is cut away to form a similar knife-edge 57 (Fig. 9) but angularly spaced by 180° from the knife edge 56. Immediately above the knife edge 57 there is formed a knife edge 58 (Figs. 8 and 12) angularly aligned with knife edge 56'. Lastly, the upper end of the cylindrical member 55 is formed with a knife edge 59 (Fig. 7) angularly aligned with knife edge 57. By providing appropriate bearing points for all four of these knife edges, the cylindrical member 55 is completely restrained from deviating from the axis 54. The various cooperating knife edge rests will now be described.

In order to support these rests, use is made 40 of a generally rectangular block 60 (Figs. 6, 8 and 9) attached to the base member 51. The knife edge rest 61 (Fig. 9) cooperating with the knife edge 57 is formed as a right angle extension of a flat strip 62. This extension 61 is resilient, and 45 exerts a restraint on the edge 57. Strip 62 is mounted as by the aid of the screws 63 upon one side of the block 60. To permit accurate adjustment of the knife edge rest 61 with relation to the knife edge 57, the strip 62 is provided with 50 the large clearance apertures 64 through which the screws 63 pass.

A similar flat strip 65 is fastened to the block 60 for forming the resilient knife edge rest 66 to cooperate with the knife edge 58 (Fig. 8).

55 Arranged on top of the block 60 is a flat strip 66' (Figs. 6 and 7) forming a knife edge seat and adapted to cooperate with the uppermost knife edge 59. A limiting stop against upward movement of the cylinder member 55 is provided by 60 the projection 67, formed on a flat strip 68 arranged above the strip 66 (Fig. 6).

The lowermost knife edge 55 is shown as co-

50 operating with the knife edge seat 68' (Figs. 6, 7 and 10). This knife edge seat may be appropriately fastened as by screws 69 to base member 51.

The knife edge rests provided by the uppermost member 66 and the lowermost member 68 form rigid seats for their respective knife edges, 70 while the intermediate seats are to some extent yielding. The extreme knife edges being oppositely faced, serve as the major guides; the intermediate seats ensure, by their resilience, that these end knife edges will be urged accurately 75 into the rigid seats.

Oscillatory movement of the cylindrical member 55, produced during the process of reproduction by oscillation of stylus 47, serves to vibrate a dynamic voice coil 70 (Figs. 7 and 11). This dynamic voice coil as will be explained herein-after vibrates axially within a narrow annular air gap. Its axis is transverse to the stylus arm axis 54. It is carried by a thin insulation cylinder 71. One end of this cylinder is formed as a spider 72 formed integrally with a tubular extension 73 (Figs. 6 and 7).

The mechanical connection between the coil support 71 and the cylindrical member 55 may be best explained in connection with Figs. 6, 7, 11 and 12. Joined to the spider 72 is a thin resilient strip-like member 74. Firmly attached as by soldering or the like to the end of this member 74 is a thin flexible strip 75 fastened into a slot in the free end of a cylindrical arm 76. This cylindrical arm in turn is firmly attached to the upper portion of the cylindrical member 55 and in general radial direction thereto.

Upon oscillation of the stylus arm 46, the arm 76 is caused to oscillate in accordance therewith. These oscillations are translated into axial oscillations of the voice or dynamic coil 70.

In order to guide the coil substantially accurately in an axial path and to provide a resilient force opposing the oscillations, use is made of a pair of supporting standards 77 and 78 shown most clearly in Figs. 6, 7 and 11. These standards are formed of thin resilient metal. They are attached as by the aid of screws 79 to a supporting block 80 fastened to the top of the base 51. The upper ends of both of these standards 77 and 78 are formed with concave saddles in which the tubular extension 76 rests. The tubular extension 76 is permanently attached to these saddles. As the coil 70 oscillates, these standards are correspondingly flexed.

The magnetic circuit for forming the annular air gap in which the dynamic coil 70 is movable is illustrated to best advantage in Fig. 17. Thus there is a pole piece 81 having an annular configuration surrounding the coil 70. This pole piece 81 may be supported as by the aid of a rectangular extension 82 (Figs. 11 and 17) abutting and fastened to the upright supporting strip 83. The lower edge of this supporting strip 83 passes through the slot 84 of the base 51 (Fig. 7) and is attached to the edge of the base 51 (Fig. 11).

Cooperating with the pole piece 81 is a cylindrical core member 85 formed as part of another pole piece 86. This pole piece 86 is also attached to the upright support 83. The cylindrical extension 85 of the pole piece 86, in conjunction with the annular member 81, defines the small annular air-gap.

In order to provide the magnetic force for producing the magnetic flux across the gap, use is made in this instance of a permanent horseshoe magnet 87 (Figs. 6, 7 and 11). This permanent horseshoe magnet is so arranged that its poles respectively cooperate with the pole pieces 82 and 86. It needs no special fastening means, as the magnetic attraction between it and pole pieces 82, 86 is sufficient to keep it in place.

Oscillations of the stylus arm 46 about the axis 54 thus corresponds to oscillations of the dynamic coil 70 in the annular air gap. Any force tending to lift the stylus 47 as by irregularities in the bottom of the record groove is

ineffective to alter the direction of relative movement between the coil 70 and the pole pieces.

The resilient extensions 61 and 66 act to maintain knife edges 56' and 59 of member 55 against their respective bearing surfaces and thus prevent relative movement in a vertical direction between stylus arm 46 and the structure of the stylus head. In this way as stylus 47 rises and falls due to irregularities in the loop 44 or roller 45 or both, the entire stylus head structure together with the attached end of a supporting arm 49 is moved up and down.

However, minute irregularities on the bottom of the record groove, such as roughness or other imperfections in the record material, which is always present to some extent, or foreign matter, may cause undesired vibratory movement of arm 46 in a vertical direction, quite analogous to movement imparted to a stylus arm by a hill and dale or vertically cut record. Such movement has a deleterious effect in the reproduction of a lateral cut record. The flexible connection 74 serves to effectively prevent any such vertical vibration of stylus arm 46 from reaching coil 70, which is effectively restricted to truly axial movement by means of supports 77, 78. No hill and dale effect of the record can therefore influence the movement of this coil.

For recording purposes, the coil 70 is fed with current impulses, and the resultant axial oscillations of the coil result in lateral vibrations of stylus 47.

In the form just described, the resilient standards 77 and 78 serve to support the dynamic coil 70, and also serve to provide a resilient resistance to vibration. In the form of the invention illustrated in Figs. 13 and 14, these effects are obtained in a somewhat different fashion. In this form of the invention, the moving coil 88 is mounted coaxially on a flexible spider 89 of light, resilient material, for example paper having the radial arms 90. The outer edge of this spring spider is attached as by screws 91 to a flange 92 provided on the annular pole piece 93. This pole piece 93 is otherwise of the same structure as the annular pole piece 81 illustrated in Figs. 6 and 7.

In this form of the invention the knife edge bearing is dispensed with. Instead, use is made of a spring hinge 94. This spring hinge 94 is firmly fastened along one longitudinal edge in a slot formed in the upright support 95, and its lower end projects through the base 98. Upright support 95 is provided with a lateral extension 96. This lateral extension is fastened as by screws 97 to the top of the base member 98. This base member 98 corresponds in general to the base member 51 of the form shown in Figs. 6 and 7.

The hinge spring 94 is provided with three laterally extending projections 99, 100 and 101, clamped in a slot formed in a movable upright member 102. This movable upright member at its lower end is provided with a saddle for the accommodation of the stylus arm 103. A strap 104 serves to attach the stylus arm 103 to the bottom of the upright member 102.

Adjacent the upper portion of the upright member 102 a radially arranged arm 105 is fastened. This arm 105 is joined as by a thin metallic member 106 to the thin metallic projection 107. This projection 107 is appropriately fastened to the end spider 108, which carries the cylindrical support 109 for the coil 88.

In this instance the stylus arm 103 is so ar-

ranged that it may yield in response to radial movement of the stylus 47 without transmitting any material force to the stylus head. For this purpose the stylus arm 103 is cut away as indicated at 110 to form a thin resilient portion in the arm 103 adjacent its supported end. Accordingly in the event there be any irregularity in the bottom of the record groove, the stylus arm 103 is merely flexed upwardly without transmitting such flexure to any of the moving parts of the translating device.

In the form illustrated in Fig. 6, the stylus arm 46 as well as the arm 76 which connects the dynamic or voice coil with the bearing structure are shown as extending in the same general radial direction. In some instances, due to the inherent mechanical resonance of the vibratory parts it may be advisable to provide angular separation between the upper connecting arm 76 and the stylus arm. This may be readily accomplished in a manner shown most clearly in Figs. 15 and 16. In this form of the invention, the stylus arm 111, similar in structure to the stylus arm 46 of Fig. 6, is disposed along a radius spaced 180° from a radius of the connecting arm 76. Furthermore in this form the alternate arrangement of the knife edge is somewhat different. The cylindrical member 112 corresponding to the cylindrical member 55 of the form shown in Fig. 6 is provided with four knife edges 113, 114, 115 and 116. The lowermost knife edge 113 is now directed toward the supporting block 117, and cooperates with a knife edge seat formed at the end of a strip 118 placed underneath the block 117. Thus the knife edge 113 is pointed toward the stylus 47, just as in the first form of Fig. 6.

The next knife edge 114 is directed away from the block 117 and is provided with a knife edge rest formed on the end of the strip 119, similar to strip 65 of Fig. 8. The third knife edge 115 is seated in the notch 120 (Fig. 16) formed on a knife edge rest 121. This knife edge rest 121 is shown as a casting integral with a block 122 to which the standards 77 and 78 are attached.

The uppermost knife edge 116 is provided with a knife edge rest formed at the extremity of the strip 123, similar to strip 62 of Fig. 9. As before the block 117 may be provided with a projection 124 extending over the axis of the cylindrical member 112 in order to limit vertical movement thereof.

In order to make it possible to utilize a mechanical push-pull principle in connection with the translating device, the stylus arm 46 may be associated with a pair of voice coils 125 and 126, as shown in the modification of Figs. 18 and 19. This form of the device is substantially the same as that illustrated in Figs. 6 and 7, except that now there are a pair of permanent magnets 87 and 127. The magnets 87 and 127, as shown most clearly in Fig. 19, are disposed respectively on opposite sides of the bearing member 55. Both of them are provided with pole piece structures corresponding to pole piece structures 82 and 86 of Figs. 6 and 7. The pole piece structures for the magnet 127 are designated by the reference characters 128 and 129. Upright support 130, corresponding to the upright support 83, is provided for these pole piece structures 128 and 129. The casing 131 is of course wider to take care of the extra width of the head. The rod 76 as before is joined to the resilient strip 74. The tubular supports for the coils 125 and 126 are joined respectively to the spiders 132 and 133.

These two spiders are in turn rigidly attached to each other as by the intervening tubular support 134 corresponding to the tubular support 73 of Figs. 6 and 7. This tubular support 134 is mounted on the resilient standards 77 and 78.

Provisions are also made in this form for making the appropriate electrical connections. Thus the center lead 135 between the coils 125 and 126 is connected to a ground connection 136, soldered or otherwise connected to an appropriate grounded part of the mechanism. The end leads 137 and 138 are joined to binding posts 139 and 140 respectively. These binding posts may be supported on an insulation block 141 fastened to the base member 142. The stylus arm thus operates to push one coil and to pull the other.

For recording purposes, if currents of proper polarities are fed to the coils 125 and 126 the effective axial forces produced by the dynamic 20 action are additive and the stylus arm 46 is correspondingly vibrated. For reproduction purposes, vibration of the arm 46 sets up currents in the coils 125 and 126 that are additive with respect to a push pull amplifier system that may 25 be connected to the coils.

Such a connection, optionally capable of recording and reproducing, is illustrated in Fig. 20. Here the dynamic stylus head 142 corresponds to the form illustrated in Figs. 18 and 19. The 30 two leads 137 and 138 and the intermediate ground connection 136 is also shown in Fig. 20.

In order to provide a balanced and sensitive circuit, free from extraneous harmonics, the microphone 143 as well as the reproducer 144 are 35 also shown as incorporating push-pull dynamic elements, shown diagrammatically in the figure.

In the event that recording is desired, the switch mechanism 145 is placed in the full line position as shown in Fig. 20. The circuits for the 40 recording operation can then be traced as follows: from the microphone 143 to the input side of push-pull amplifier system 146. This push-pull amplifier system has its output circuit connected as by leads 147 and 148 to the stationary 45 contacts 149 and 150 respectively, of switch 145. Switch blades 151 and 152 then connect by way of leads 153 and 154 to the input side of another push-pull amplifier system 155. The output of this amplifier system is connected by leads 156 and 157 to the switch arms 158 and 159 respectively. The contact points 160 and 161 contacted by these switch arms are joined to the leads 137 and 138 for operating the head 142. Thus as the circuits are now established, operation 50 of microphone 143 causes operation of the stylus head 142 to cut a lateral record.

For reproducing purposes, the switch blades are moved as by a common actuating rod 162 so as to assume the dotted line position. When this 60 is effected, the microphone 143 is disconnected and the speaker 144 is connected in a manner now to be outlined.

The stylus head 142 now operates as a pickup head. Output lead 137 connects by way of contact point 160 and connection 163 to the switch blade 164; thence by connection 165 to the input lead 154 of amplifier 155. The other input lead 153 connects by way of conductor 166 to the contact point 167, which is now in contact with 65 switch arm 168. This switch arm is connected by way of connection 169 and contact point 161 to the other output lead 138 of the stylus head 142. Thus the output of the stylus head is connected to the input side of the push-pull amplifier 155. The output lead 156 of amplifier 155 con-

nects by way of switch blade 158 to the contact point 170 of switch 145, and thence by way of connection 171 to one of the leads of the push-pull dynamic speaker 144. The other lead 172 of this speaker connects by way of switch contact 173 and switch blade 159 to the other output lead 157 of the amplifier system 155. Thus the loud speaker 144 is connected to the output side of the amplifier 155.

It has been determined experimentally in connection with push pull voice coils as 21 and 22, that if these coils are each partly within and partly without the air gap, greatly improved results are obtained. Figs. 1, 4 and 19 all disclose the coils so arranged. Referring to Fig. 21, which is a large scale detail of the coils of Fig. 1, showing the coils 21, 22 at rest or in their neutral position, it will be seen that the coils are symmetrically arranged on supporting tube 23 with respect to air gap 19 and recesses 33, 34, but in opposite senses, that is coil 21 projects out of the air gap toward the left and coil 22 projects out of the air gap toward the right. Thus each coil 21 and 22 is unsymmetrically arranged in its respective gap, although the two coils are symmetrically disposed on opposite sides of a plane of symmetry normal to the gaps. Each coil 21, 22 has its mid-point adjacent the respective end of the gap 19, preferably so located that somewhat over half the length of the coil is outside the air gap. Similarly, in Fig. 19, coils 125 and 126 have a substantial portion of their windings outside their respective air gaps. When number 23 is urged to the right from the neutral position (Fig. 21) by the stylus, coil 21 takes dominance since it is moving into the magnetic field; when it moves to the left coil 22 similarly takes dominance. Since the vibrations of the stylus in reproduction cause such alternate movement of the coils, a push pull effect is impressed on the amplifier. In recording, the output from a push pull amplifier influences coil 21 and 22 with alternately greater intensity in a generally similar manner.

What is claimed is:

1. In a device of the character described, a stylus arm, means mounting said arm to permit vibratile movement of said arm about an axis, a translating device cooperating with the stylus arm and having an element mechanically connected to said arm, so as to vibrate in accordance with the vibrations of the arm about said axis, and means ensuring that vibrations of the arm about any axis transverse to said axis produces substantially zero motion of the said element with respect to other parts of the translating device.

2. In a device of the character described, a vibratory stylus arm, a knife-edge bearing structure for the arm, said bearing structure having axially and angularly spaced knife edges, to restrain vibration of the arm about an axis, and a translating device cooperating with the arm.

3. In a device of the character described, a vibratory stylus arm, an elongated bearing structure associated with the arm to restrain vibrations of the arm about an axis, said structure including a series of axially spaced knife edges, said knife edges being angularly spaced around the axis, said arm being supported adjacent one end of the bearing structure, a translating device having a movable element, and a connection between the element and the other end of the bearing structure.

4. In a device of the character described, a

vibratory stylus arm, an elongated bearing structure associated with the arm to restrain vibrations of the arm about an axis, said structure including a series of axially spaced knife edges, said knife edges being angularly spaced around the axis, said arm being supported adjacent one end of the bearing structure, a translating device having a movable element, a connection between the element and the other end of the bearing structure, and an extended resilient support for the element.

5. In a device of the character described, a vibratory stylus arm, a knife-edge bearing structure for the arm, said bearing structure having a pair of axially spaced knife edges and knife edge seats to restrain vibration of the arm about an axis, said knife edges being angularly spaced from each other and means acting intermediate the knife edges for resiliently urging the knife edges against their seats.

6. In a device of the character described, a vibratory stylus arm, means cooperating with the arm for restraining the vibrations about an axis, said arm being adapted to yield in a direction transverse to the vibrations, and a translating device having a movable element mechanically connected to the arm.

7. In a device of the character described, a vibratory stylus arm, a spring hinge cooperating with the arm and restraining vibrations of the arm about an axis, means forming a magnetic air gap, a coil axially movable in the gap, means resiliently supporting said coil in the gap, and a connection between the coil and the arm.

8. In a device of the character described, a vibratory stylus arm, a spring hinge cooperating with the arm and restraining vibrations of the arm about an axis, said arm yielding resiliently in a direction transverse to the vibrations, means forming a magnetic air gap, a coil axially movable in the gap, means resiliently supporting said coil in the gap, and a connection between the coil and the arm.

9. In a device of the character described, a vibratory stylus arm, an elongated bearing structure for restraining the vibrations of the arm about the axis of the structure, said arm being disposed adjacent one end of the structure, a pair of means forming a pair of annular magnetic air gaps, said gaps being coaxial but spaced along their common axis, said common axis being transverse to the axis of vibration, a pair of coils respectively disposed in said gaps, and a connection between the other end of the moving part of the bearing structure and connected to both coils.

10. In a device of the character described, a stylus arm, a stylus carried by the arm, and disposed transversely of the arm, a knife-edge bearing structure for the arm, and having an axis transverse to the arm, said bearing structure having axially and angularly spaced knife-edges, and a translating device cooperating with said arm.

11. In a device of the character described, a stylus arm, a stylus carried by the arm, and disposed transversely of the arm, a knife-edge bearing structure for the arm, and having an axis transverse to the arm, said bearing structure having axially and angularly spaced knife-edges, as well as at least one resilient knife-edge seat, cooperating with one of said knife edges, and a translating device cooperating with said arm.
